OIL BURNER CONTROL—VARIABLE RESISTANCE WITH TEMPERATURE TYPE

Raymond H. Sullivan, Rochester, N. Y., assignor to General Motors Corporation, Detroit, Mich., a corporation of Delaware

Application June 17, 1936, Serial No. 85,646

1 Claim. (Cl. 158—28)

This invention relates to control systems and more specifically to control systems adapted to be utilized with fluid fuel burners.

In a great many of the systems for controlling fluid fuel burners the use of contacts operated by the temperature within the combustion chamber or stack has resulted in a great deal of trouble due to the sticking contacts since the whole operating portion is subjected to some amount of heat and the bimetallic or movable part subjected to even higher temperatures.

It is the object of this invention to provide means controlled by the combustion temperature for operating various portions of the circuit without the necessity of moving parts and attendant sticking or burning of contact points.

With the above and other objects in view which will become apparent as the specification proceeds, my invention resides in the construction as utilized in the following specification and claim and illustrated in the accompanying drawing, in which:

The figure shows a schematic diagram of a control circuit utilizing the principles of my invention.

The main lines 2 and 4 may be attached to any source of electrical energy and have connected across them the primary 6 of a transformer 8. The secondary 10 of the transformer 8 has one end connected by line 12 to one contact 14 of a high limit switch designated generally at 16, the other contact 18 of said switch being connected by line 20 to one terminal of a warp switch 22, the movable terminal of said switch being connected by line 24 to one end of a resistance 26. The resistance 26 is of the type whose resistivity changes appreciably with the change in the temperature thereof and may be of nickel or nickel alloy.

Connected in series with the resistance 26 is a second resistance coil 28 whose opposite terminal is connected by line 30 to one terminal of the room thermostat 32, the opposite terminal 34 of which is connected by line 36 to the other end of the secondary 10. The resistance means 28 is formed of advance wire or some other material which has a small resistance temperature coefficient so that as the temperature changes there is a very small change in the resistivity of the means. Connected directly across the resistance means 28 is a relay coil 38 by wires 40 and 42, said coil being operated by the potential drop across said resistance.

From the contact 32 of the room thermostat runs a wire 44 which extends to a second relay

coil 46, the opposite terminal of which is connected by wire 48 back to the wire 24.

Also extending from the wire 36 is a wire 50 which extends to one end of the resistance heating coil 52 of the warp switch 22, the other end 5 of the heating coil being connected by wire 54 to contact 56. A movable contact member 62 is adapted to cooperate with contact 56 to close a circuit between wire 64 and wire 54, said wire 64 extending back and connected to line 12. 10

All of the circuits described thus far, with the exception of the incoming lines, have been low voltage circuits and include in the main the controlling apparatus. To the incoming line 2 is connected a wire 66 which extends to contact 68 15 and cooperates with a movable contact 70 which is connected by wires 72 and 74 to one side of the motor 76. The opposite side of the motor is connected by lines 78 and 80 to the other incoming line 4. Line 72 also extends down and is 20 connected to a stationary contact 82 which cooperates with the movable contact 84, the latter being connected by line 86 to one side of the primary 88 of the ignition transformer, the opposite side of the primary being connected to line 25 80 which extends back to the incoming line 4. The secondary coil 90 of the ignition transformer has connected across it a spark gap 92.

From the foregoing it will be seen that the only portions of the apparatus in the high voltage circuit are the motor for discharging the fuel into the combustion chamber and the ignition transformer, the remainder being all low voltage.

With respect to the high limit control mentioned above, this control embodies a magnetic member 94 which is subjected to the heat of combustion in the stack and under normal temperatures will retain the contacts 14 and 18 in closed position. However, if the temperature becomes too high the magnetism of the device will be changed to such an extent that the circuit will open and cause the whole system to be de-energized.

The operation of this circuit is as follows:

Under normal inoperative conditions the warp switch 22 is closed, the relays 38 and 46 are de-energized, the room thermostat is open and the motor is in rest position. If, now, the temperature of the space to be heated has fallen to such 50 a degree that the contacts of the room thermostat close, a circuit is completed from the transformer secondary 10, through line 36, contact 34, contact 32, line 44, relay 46, line 48, line 24, switch 22, line 20, contacts 14, 18 and line 12 back to 55

the secondary. This energizes the relay 46 which closes contact 70 against contact 68 which starts the burner motor in operation through an obvious circuit. At the same time a circuit is completed through the two resistances 26 and 28 in series as follows: Secondary 10, line 36, contacts 34, 32, line 30, resistance 28, resistance 26, line 24, switch 22, line 20, contacts 18, 14 and line 12 back to the secondary 10. This causes a definite potential drop across the resistance 28 and gives sufficient voltage to operate relay 38 through an obvious circuit which closes contacts 84, 82 and 62, 56. The closing of the first pair of contacts completes the circuit from lines 12 and 30 to the primary 88 of the ignition transformer which causes sparks to jump through the gap 92 and ignition of the oil will normally follow. The closing of the contacts 62, 56 places the heating coil 52 of the warp switch across the transformer secondary by the following circuit: Secondary 10, line 12, wire 64, contacts 62, 56, line 54, coil 52, line 50 and line 36 back to the transformer secondary. Under normal conditions the combustion chamber will be heated and the resistivity of the resistance 26 will be increased to such an extent that the voltage drop across the resistance 28 will decrease and the relay 38 will have insufficient strength to retain the movable contacts 62 and 84 in their uppermost position. These two contacts will then drop out, the second contact opening the circuit to the ignition transformer primary and the first contact opening the circuit through the warp switch heating coil 52. The ignition will therefore be cut off after a pre-

determined time and also the warp switch coil will be prevented from operating. If, however, the burner does not start and the relay 38 maintains an energized condition, the warp coil will, after a certain set predetermined period, cause its contacts to open by the bending of the bimetal strip and the whole circuit will be de-energized. Also, if through some difficulty or fault, the furnace is allowed to heat up to an abnormal temperature, the high limit control 16 will drop its contacts and cause the contacts 14, 18 to open which also deenergizes the whole system. 5 10

I claim:

In a room heating system, a combustion chamber, a fluid fuel burner, means for propelling fuel into said combustion chamber, fuel igniting means, an electric control circuit including a thermal resistance exposed to the heat of said combustion chamber for controlling said igniting means, a room thermostat for regulating said burner, a second circuit for controlling said fuel feeding means, a circuit closer in said second circuit, a permanent magnet, the magnetization of which varies inversely with variation of temperature without demagnetization, said magnet being exposed to spent combustion products of said burner for normally holding the circuit closer of said second circuit closed, and means for opening said circuit closer when the magnetization of said magnet has been diminished to a predetermined degree by rise of temperature. 15 20 25 30
